UNITED STATES PATENT OFFICE.

HUGH AUGUSTINE RILEY, OF HOOSICK FALLS, NEW YORK, ASSIGNOR TO
DENNIS J. WHELAN, OF TROY, NEW YORK.

GUTTER-FORMER.

SPECIFICATION forming part of Letters Patent No. 614,624, dated November 22, 1898.

Application filed February 3, 1898. Serial No. 668,973. (No model.)

To all whom it may concern:

Be it known that I, HUGH AUGUSTINE RILEY, a citizen of the United States of America, and a resident of Hoosick Falls, in the county of Rensselaer and State of New York, have invented certain new and useful Improvements in Gutter-Formers, of which the following is a specification.

This invention relates to improvements upon the machine which forms the subject-matter of the application for United States Letters Patent of Earl G. Watrous, serially numbered 641,152, filed June 17, 1897, for improvement in gutter-formers.

The improvements embraced in the present invention comprise means for transposing the rollers to make different sizes of gutter without taking the machine in pieces, as required in the former machine, in providing means for firmly holding in position the roller which carries the beading-mandrel during the process of rolling up the bead, in provisions whereby any of the rollers or the beading-mandrel may be removed from the machine without disarranging any of its parts, and in an improved supporting roller-brake which is adapted to prevent small rollers from springing away from the companion roller in forming a long piece of gutter.

The invention is fully disclosed in the drawings, wherein—

Figure 1 is a plan view of my machine as improved, the central portion of the rollers being broken away. Fig. 2 is an end elevation of the machine. Fig. 3 is an elevation of one end of the front of the machine. Fig. 4 is a perspective view of one of the journal-brackets. Fig. 5 shows the relative position of the parts while the beading-mandrel is passing down between the two forming-rollers in the process of rolling up a piece of gutter. Fig. 6 shows how the rollers are forced together after the beading-mandrel has passed out from contact with the presser-roller. Fig. 7 shows the position of the parts after the gutter-plate has passed out from between the forming-rollers. Fig. 8 is a side view of my improved roller-brake for holding the rollers together. Fig. 9 is a plan view of the same. Fig. 10 is a diagrammatical view showing the position of the co-operative parts of the brake

during the passage of the beading-mandrel between the bending-roller and the lower roller of the brake. Fig. 11 is a similar view of the position of the parts when the mandrel has reached a point opposite the interval between the two brake-rollers. Fig. 12 shows the position of the parts as the mandrel is passing out from under the upper brake-roller.

The machine will first be described in connection with the drawings, after which the particular features of invention will be pointed out in the claims.

Two journal-stands 11 are provided upon which my improvements are mounted, which may be attached to a platform or bench in any convenient way. These are preferably made rights and lefts, and each is provided with an open journal-bearing 2 for receiving and supporting the journals of one of the two rollers of the machine. Whichever of the two rollers is carried in these bearings is called the "presser-roller." In this case this roller is marked 14. It consists of a piece of metallic pipe fitted with a head 16 at each end, from which project the journals 17 17, which terminate in squared ends *ff* for the purpose of taking on a crank 19, by which it may be rotated when used as a forming-roller. The bearings 22 have an inclined opening toward the companion roller and are so made that the outer lip or jaw will overhang the journal to prevent the roller lifting in the working of the machine. The forming-roller is shown at 15 and in all respects, except in size, is like roller 14. Both rollers are fitted with a series of tapped screw-holes *g g g g* for the attachment of a series of mandrel-retaining clips 24 24, of which two are shown in the drawings. Each of these clips is attached to the roller by a screw or screws *e e*, &c. These clips are transferable from one roller to the other, as occasion requires. These clips constitute the bearings or supports for the beading-mandrel 25, in which it revolves. This mandrel is a cylindrical rod grooved from end to end, as seen at 26, to receive the edge of the sheet of metal to be formed up, and is fitted at one end with a flanged collar 27, which is rigidly attached to the mandrel, so that it cannot be slipped

thereon lengthwise. This flange overhangs the end of the roller to which it is attached, which prevents movement of the mandrel thereon in one direction, while movement in the other direction is prevented by a flanged lip 18, which is secured to the end of the roller. Both ends of the mandrel are squared to take on cranks by which the bead is rolled up, and sufficient space between the surface of the mandrel and the interior of the clips 24 is allowed to provide for the thickness of the sheet metal undergoing manipulation.

The forming-roller operates in open bearings which permit the journals to have a sliding movement toward and away from the presser-roller, and which are formed as follows: The upper edge 3 of standards 1 1 is straight, and the journals of the forming-roller rest thereon. The journal-brackets 55 have each a shoulder 13, which rests on the edge 3 when the bracket is in place. Each bracket has a forwardly-overhanging arm 11, which projects out over the edge 3 and constitutes the cap to the bearing in which the journals of the forming-roller 15 revolve. In other terms, these journals ride and turn in the gap thus formed between the edges 3 3 and the under edges of the arms 11 11, as seen in Fig. 2, which is open on the side toward the presser-roller, so that, if necessary, after lifting the presser-roller out of its bearings the forming-roller may be slid forward and be similarly lifted out of its position. Thus it will be seen that the rollers are interchangeable both as to their locations in the machine and as to their endwise positions.

The journal-bracket 5 (shown in Fig. 4) has a horizontal recess 6, which shuts over corresponding rib 4 on the stand 1 when in position. It is confined to the stand by means of a bolt 7, which passes through a hole in the plate 8 of the bracket and an elongated slot in the stand 1, as shown in dotted lines in Fig. 2. Rib 4, in connection with the groove 45 in the bracket and the bolt 7, afford means for adjusting the bracket toward and from the presser-roller to accommodate it to different sizes of rollers. It has projecting from one side the cam-abutment 9, the back or 50 operative edge of which consists of the concave *b* and the ledge 10. The latter parts are designed to coöperate with the edge of the crank-cam 20, which is an integral part of crank 19. This crank-cam is centrally perforated with a square hole to fit the squared ends of the journals of the forming and presser rollers and has a gap 23 cut out of its periphery to allow the socket of the heading-roller crank to be applied to the ends *h h* of 55 the mandrel 25, and also to allow the finished length of gutter to be removed or drawn off from the mandrel. One side of the cam-disk 20 is cut away, as on the line from 21 to 22, for the purpose of securing the appropriate 60 means in connection with the cam-abutment 9 for holding the mandrel 25 in a fixed position while it is being turned to roll up a bead,

which function is effected by turning it in the direction of the arrow, as in Fig. 2, and also for the purpose of allowing the forming-roller 78 to recede from the presser-roller while the mandrel is passing downwardly between the two rollers and after such passage to close up against the presser-roller firmly with the metal plate between them, as in Fig. 6. The 75 performance of these functions will more 80 appear in the description of the operation of the machine.

Any number of rollers within reasonable limits may be employed in this machine, 80 which may be combined or interchangeably used in any desired way. The mandrel-clips may be made so as to take in mandrels of one-half, five-eighths, or nine-sixteenths of an inch, or, if desired, different clips to closely 85 fit the different-sized mandrels may be employed. This is only a matter of judgment with the operator.

The operation of the machine is as follows: Selection is first made of the particular roller 90 and beading-mandrel upon which it is desired to form the gutter. The mandrel is then laid in position along the surface of the roller and the clips are secured in position over the mandrel. Thus equipped the forming-roller is 95 put in position in its bearings under the caps 11 11. Another roller is then selected to serve as a presser-roller, which is likewise dropped into its bearings 2 2 on the stands. The cam-cranks are then applied to the journals of the 100 forming-roller and the cam-disk 20 turned to the position shown in Fig. 7 or so that its concentric edge will come opposite to and in contact with the concave portion *b* of the abutment 9. The clamping-bolts 7 7 being loosened 105 the brackets 55 are then crowded toward the presser-roller until the two rollers make contact with the thickness of a piece of the sheet metal to be operated upon between them, although the presence of the metal may 110 not always be necessary. In this position the bolts 7 7 are tightened and the machine is 115 ready for use. In use the first thing is to rotate the cam backward until the shoulder 21 rests on the ledge 10 of the abutment. This 120 brings the mandrel or beading-roller 25 into the position seen in Fig. 2, and the same is then turned, so that the groove 26 will open upwardly to receive the edge of the sheet-metal plate. The corner of the plate is then 125 entered in the open end of the slot 26 opposite the collar 27 and is slid into its proper position over the rollers. When so placed, the beading-cranks (not shown) are applied to the ends of the mandrel and are turned toward the shoulder 10 or in the direction of the arrow until a full turn or thereabout has 130 been made. In doing this it will be seen that the engagement between the shoulder 21 and ledge 10 offers firm resistance to the winding action of the cranks, and thus facilitates a steady and true formation of the bead. The absence of this feature from the machine on which this is an improvement was a serious

defect, as extraneous instead of automatic means of resistance to this winding force had to be supplied. The bead having thus been formed the beading-crank are removed and the cam-crank are started, turning in a direction opposite to that of the beading-crank or in the direction shown by the arrows in Figs. 5, 6, and 7. As this turn progresses the clips 24 first contact with the presser-roller, and further movement tends to crowd the forming-roller backwardly away from the presser-roller until the highest point of the clip is brought down onto the plane of the centers of the rollers, as seen in Fig. 5. To facilitate this recession of the forming-roller, the edge of the cam 20 is cutaway, as between 21 and 22; but the instant the clips have passed below dead-center line, so that there is freedom for the forming-roller to move toward the presser-roller, the point 22 of the cam engages the point *c* of the abutment 9, and further movement of the cranks by virtue of the fulcrumage thus created throws the forming-roller toward the presser-roller and carries the sheet metal against it. From this point the concentric part of the cam-disk between the points 22 and the gap 23 enters the concave *b* of the abutment 9 and by means of such curved abutment holds the plate firmly between the forming and presser rollers during the remaining portion of the revolution of the forming-roller until the plate runs out from between the two rollers, when, being released therefrom, it falls away from the forming-roller, as in Fig. 7, and remains hinged, as it were, to the beading roller or mandrel, from which it may be detached by rolling the forming-roller to a position to carry the mandrel to the upper side, when the length of completed gutter may be drawn off from the mandrel through the gap 23, when by a further forward movement of the cam-crank the clips will be carried over against the presser-roller, thus crowding the forming-roller back to the position of Fig. 5. From this last position a reversed movement of the cam-crank throws the shoulder 21 over onto the ledge 10 and leaves the machine in its original position, as in Fig. 2, ready for a new operation.

From experience in the use of machines in which very long rollers of small diameter have been employed it has been found that in the center of the smaller roller it would spring away from its companion roller and not keep the sheet metal in the process of rolling it up against the other roller, and as a result the gutter at this point would be only imperfectly shaped. On account of the obstruction offered by the beading-mandrel in passing between the two rollers, as hereinbefore explained, some device was called for which would not only hold the roller against the plate while the cylindrical part of the rollers were in contact, but would also hold the springing roller to its work while the mandrel was passing between the rollers, as seen in Fig. 5. For this purpose the apparatus shown in Figs.

8 and 9 has been devised. It consists of a stand-bracket 40, which is attached to the machine-bench 60 by means of the bolt and nut 70 42 43 and the slot 41, whereby the stand is rendered transversely adjustable in relation to the rollers. A lever 46 is pivoted to the top of this bracket at 47, between the forks of which a roller 48 is pivoted. From the 75 lower part of the bracket, as at 54, is hung a stirrup 44, which carries the roller-frame 50, pivoted at 49. This roller-frame also carries the two rollers 51 and 52, which are designed to bear against the gutter-plate or against the 80 surface of the roller upon which the plate is bent. The stirrup 44 has a cross-bar 45 behind the bracket 40, against which the brake-lever 46 strikes when the brake-handle is dropped, whereby the stirrup is thrown back, 85 so as to withdraw the rollers 51 and 52 from contact with the roller 15 and hold them back out of the way. When the handle is dropped, the parts take the positions indicated by the dotted lines in Fig. 8. In use the brake-roller 90 48 is designed to bear against both the stirrup-rollers 51 and 52, and by lifting the handle the stirrup-rollers will be thrown against whatever may be carried against them in process of revolving the roller 15. By raising or 95 lowering the hand the brake-roller will follow the oscillating movements of the rollers in the frame 50 and by doing so will force both the stirrup-rollers against the roller 15 or one against the mandrel and the other against 100 roller 15 or both against the mandrel, as in Fig. 11, and the mandrel against the roller 15; but in every case the pressure applied to the brake-roller will be transferred to the roller 15, and thereby it will be prevented 105 from springing outwardly or away from its companion roller 14. By this yielding combination of levers, roller-frames, and rollers it is entirely feasible to revolve the beading-mandrel under the brake-roller without its pressure being at any point withdrawn from the gutter-plate or the forming-roller, according to whichever of the two may be in contact with the stirrup-rollers.

Having thus described my machine, what 115 I claim as my invention, and desire to secure by Letters Patent, is—

1. The combination in a gutter-former with a presser-roller carried in fixed bearings and a forming-roller carrying a bead-forming mandrel; of elongated bearings for the forming-roller in which its journals can both turn and slide toward and away from the presser-roller and means for forcing and holding the forming-roller to its duty in connection with the 120 presser-roller in the bending of a plate.

2. In a gutter-former the combination with a presser-roller carried in fixed bearings open at one side to permit removal of the roller therefrom, and a forming-roller carrying a 130 bead-forming mandrel, of elongated bearings for the forming-roller in which its journals can both turn and slide toward and away from the presser-roller and means for forcing and

holding the forming-roller to its duty in connection with the presser-roller in bending a plate to form a gutter.

3. In a gutter-former the combination with 5 a presser-roller carried in fixed bearings and a forming-roller carrying a bead-forming mandrel, of elongated bearings for the forming-roller open toward the presser-roller to permit ready removal of the forming-roller therefrom and in which its journals can both turn and slide toward and away from the presser-roller, and means for forcing and holding the forming-roller to its duty in connection with the presser-roller in the bending of a plate to 15 form a gutter.

4. The combination with the beading-mandrel mounted on the forming-roller, of the forming-roller and means connected therewith for preventing its rotation and resisting 20 the tendency of the mandrel-crank to turn in the same direction as the mandrel turns in the process of rolling up a bead.

5. The combination with the stands and journal-brackets having the elongated journal-bearings, of the forming-roller carrying the beading-mandrel, the crank-cam having the shoulder and the ledge on the bracket which coöperates therewith.

6. The combination of a stand which forms 30 the lower member of an elongated open journal-bearing, with an adjustable bracket having an arm which overhangs said lower member and forms the upper member of said bearing.

35 7. In a gutter-former, the combination with two coöperative bending-rollers, of a pair of detachable cranks adapted to fit either roller, and bearings in which said rollers rest in operation, all of which bearings open in a direction opposed to the line of thrust in bending a plate, as a means of promoting interchange or transposition of the rollers.

8. The combination with a forming-roller of a pair of bearing-rollers carried in an oscillatory frame which is hung in a swinging stirrup pivoted to a stand upon which is pivoted 45 a brake-lever which carries a roller that is adapted by the movement of the brake-lever to be brought to bear against one or both of

the bearing-rollers to crowd them against the 50 forming-roller, or against any material carried by or being formed thereon.

9. The combination with the forming-roller and beading-mandrel carried thereon, of a pair of bearing-rollers carried in an oscillatory 55 frame which is hung in a swinging stirrup pivoted to a stand upon which is pivoted a brake-lever which carries a roller that is adapted by the movement of the handle of the brake-lever to be brought to bear against one or both 60 of the bearing-rollers to crowd them against the forming-roller, or against any material carried by or being formed thereon.

10. The combination with the bracket-stand and brake-lever of the pivoted stirrup carrying 65 the oscillatory roller-frame and bearing-rollers and having a rearward extension which projects into the path of the brake-handle when it drops for the purpose of throwing the bearing-rollers out of their normal field of 70 duty.

11. In a gutter-former, the combination with a pair of forming-rollers one of which carries a beading-mandrel, of a transversely-adjustable brake-bracket upon which is hung a 75 swinging stirrup that carries an oscillatory frame in which are pivoted two rollers adapted to bear against one of the forming-rollers or against any material being formed theron, and a brake-lever carrying a roller that is 80 adapted to bear against one or both of the stirrup-rollers.

12. As a provision for maintaining continuous contact and pressure against a moving irregular surface, three rollers, two of which 85 are pivoted in a frame which is itself pivoted in a movable carrier, and the other roller is pivoted in a movable member which is under operative control, the latter roller being connected with means adapted to force it into 90 tangential contact with both the other rollers.

Signed by me, at the city of Troy, Rensselaer county, New York, this 13th day of January, A. D. 1898.

HUGH AUGUSTINE RILEY.
